UNITED STATES PATENT OFFICE.

FRANK H. ARMSTRONG, OF AUBURN, NEW YORK, ASSIGNOR TO CORONA TYPEWRITER COMPANY, INC., OF GROTON, NEW YORK. A CORPORATION OF NEW YORK.

TYPEWRITING MACHINE.

Application filed September 17, 1920. Serial No. 410,960.

To all whom it may concern:

Be it known that I, FRANK H. ARMSTRONG, a citizen of the United States of America, and a resident of Auburn, county 8 of Cayuga, State of New York, have invented certain new and useful Improvements in Typewriting Machines, of which the following is a specification.

This invention relates to improvements in typewriting machines, and more particularly to means for varying the relation between the type-carrying means and the platen of such machines to permit the printing of letters or characters of different case 15 from a single type-carrier in machines having type-carriers each of which is provided with a plurality of types.

In the preferred embodiment of the invention shown in the drawings, the change 20 of case is effected by shifting a type-bar hanger or segment in a vertical plane relatively to the machine frame, the construction illustrated being designed for use in a front-strike portable typewriting machine 25 having a platen and carriage foldable forwardly over the keyboard in a manner similar to the well-known "Corona" typewriter. It will be obvious, however, that the invention may be embodied in non-compactible 30 as well as compactible machines, and in machines in which the change of case is effected by shifting the platen. It will be understood also that, while I have shown a mechanism in which the shiftable support 35 moves vertically, the invention is not limited to shift mechanism in which a segment or platen is moved in a vertical plane to change the case.

The invention has for its objects to provide improved means for imparting a double case-shift movement to a type-bar segment or a support shiftable to change the relation between the type-bars and platen of a typewriter; to provide improved antifriction means for supporting and guiding a type-segment carrier in a segment shift machine; to provide a case-shift mechanism practically all of the parts of which are formed of sheet metal; to provide improved means whereby a case-shift movement may be imparted to a type-bar support from duplicate sets of "Cap." and "Fig." shift keys located at opposite sides of the keyboard of a machine; to provide 55 a support shiftable to change case and sup-

ported at three points only by antifriction bearings; to provide antifriction supporting and guiding means for a segment-carrier or other member shiftable to change case in which wear in all the bearings is automatically taken up; and to provide antifriction guiding means at opposite sides of a support which is shiftable to change case so constructed that the companion race-way members of all the bearings are forced 65 toward each other by a single spring.

Other objects of the invention will more fully appear from the description of the invention with reference to the accompanying drawings, in which—

Fig. 1 is a plan view of the case-shift mechanism, the segment being removed to more clearly illustrate the operating mechanism;

Fig. 2 a plan view of the segment and its 75 shiftable support or carrier;

Fig. 3 a vertical longitudinal sectional view taken centrally of the machine, the parts being shown in normal position;

Fig. 4 a view similar to Fig. 3 showing 80 the "Cap." shift position of the parts;

Fig. 5 a view similar to Fig. 3 showing the parts in "Fig." shift position;

Fig. 6 a front elevation of the shift mechanism, parts of the frame and mechanism 85 being broken away;

Fig. 7 a front elevation showing the segment-carrier and the antifriction bearings therefor;

Fig. 8 a perspective view of the stationary bracket located at the rear of the carrier;

Fig. 9 a fragmentary perspective view of the shift mechanism;

Fig. 10 a detail view showing a part of 95 the shift frame;

Figs. 11 and 12 fragmentary side elevations showing the rear portions of the "Cap." and "Fig." shift levers, respectively;

Fig. 13 a horizontal sectional view on the line XIII—XIII of Fig. 7;

Fig. 14 an end view of the upper left-hand raceway member on the segment carrier;

Fig. 15 a horizontal sectional view on the line XV—XV of Fig. 7;

Fig. 16 a sectional view taken on the line XVI—XVI of Fig. 7;

Fig. 17 a perspective view of the upper 110

stationary raceway member and the bracket on which it is formed located at the left-hand side of the carrier;

Fig. 18 a perspective view of the pivotally supported raceway member and the angular arm on which it is formed; and

Fig. 19 a perspective view of the link which forces the two lower centrally located raceway members toward each other.

- 10 In the construction illustrated in the drawings, the main frame of the machine is formed of pressed steel in one piece and comprises side walls 1 connected by a rear wall 2 and a front rail 3. A sheet metal bracket 4 is rigidly secured to the front face of the rear wall 2 by four screws 5 at a point midway between the side walls of the frame. Bracket 4 is provided with a forwardly projecting arm adjacent its lower 20 end lying in a vertical plane and doubled upon itself to form a raceway member 6. The inner portion of the doubled member 6 is provided with a ball channel 7 facing toward the longitudinal center line of the 25 machine and cooperating with an outwardly facing ball channel 8 in a forwardly extending doubled raceway member 9 formed integrally with an integral arm or stem 10 depending from the lower edge of a sheet metal 30 segment-carrying plate 11. The segment carrier 11 is of general arcuate form so as to conform substantially with the curvature of a curved type-bar hanger or segment 12 detachably held thereto by three screws 13. 35 The segment carrier is only slightly larger than the segment and arm 10 on the carrier is located midway the ends of the carrier. The channels in both raceway members 6 and 9 are of similar construction, being V-shaped in cross-section and formed by slitting the rearwardly extending portion of the 40 doubled member forwardly from its rear edge adjacent both the upper and lower edges of said portion and pressing the metal intermediate the slits toward the other portion 45 of the member to form the ball channel. The base of the ball channel rests against the forwardly extending portion of the doubled member, thus bracing the channel-carrying 50 portion of the raceway member. The two fingers or tongues 14 at the upper and lower ends of the raceway channels prevent the ball 15 in the raceway formed by channels 7 and 8 from traveling beyond the ends of the 55 channels and dropping out of the raceway. The channeled portion of each of the raceway members is preferably provided along its rear edge with a stiffening flange, as shown, lying in the same vertical plane as 60 the ball-stop fingers 14. The forwardly extending portion of raceway member 6 is provided at its upper and lower edges with bracing lugs 16 bent outwardly and engaging the front face of bracket 4 at their rear 65 edges.

The transversely extending portion, or main body portion, of the segment carrier 11 is provided at each end with integral, forwardly projecting, doubled raceway members or arms 17 of the same construction as raceway member 9, said members lying in a vertical plane and being provided with outwardly facing ball channels 18 and ball-stop fingers 19 formed in the same manner as the channels and fingers on members 6 and 9. 75

The ball channel 18 in the left-hand raceway member 17 cooperates with an inwardly facing ball channel 20 in a similar doubled raceway member 21 projecting forwardly from the inner side of a bracket 22 rigidly held by screws 23 to the rear wall 2 of the machine frame adjacent the left-hand side of the machine. The raceway member 21 is provided with ball-stop fingers 24 and a ball 25 is confined in the raceway formed by channels 18 and 20. Member 21 is also provided with bracing lugs 26 engaging the front face of bracket 22. The ball channel 18 in the right-hand raceway member 17 cooperates with an inwardly facing ball channel 27 in a doubled raceway member or arm 28 formed on and extending forwardly from the upper end of an angular arm 29 pivotally held at 30 to a laterally extending arm 31 formed on the bracket 4. Member 28 is provided with bracing lugs 32 which engage the front face of arm 29 and is also provided with ball-stop fingers 33. A ball 34 is confined in the raceway formed by channels 18 and 27 in the complementary raceway 90 members 17 and 28. 95

The depending central or stem portion 10 of the segment carrier 11 is provided with an integral angular arm 35 opposite the raceway member 9 to which the inner end of a thrust link 36 is connected by a separably interlocked pivotal connection. The shank of a forwardly bent T-shaped lug 37 on the inner end of the link 36 extends through the slot 38 in the outer end of arm 35 and bears against and rocks on the rounded inner edge of the slot. The engagement of the T-lug 37 and fingers 39 on link 36 with the slotted portion of arm 35 prevents separation of the link from the arm by movement in any direction, except toward the right of the machine, while permitting the necessary pivotal movement of the link when the carrier moves vertically. The link 36 is pivotally connected at 40 with the longer lower arm of a normally vertically extending lever 41, the shorter upper arm of which is connected by a coiled spring 42 with the angular pivoted arm 29 which carries the raceway member 28. Lever 41 is pivotally held at 43 to an arm 44 on bracket 4 and spring 42 is under tension and constantly tends to swing arm 29 toward the left and (through lever 41) also constantly tends to thrust link 36 toward the left. It will thus be seen that spring 130

42 not only yieldably forces raceway member 28 toward raceway member 17 at the right hand end of the carrier, but also yieldably forces the carrier bodily toward the left 5 through arm 29 and through lever 41 and link 36 and thus yieldably forces raceway member 9 and the raceway member 17 at the left-hand side of the carrier toward the fixed raceway members 6 and 21. Wear in all 10 three of the raceways will thus be automatically taken up by the single spring. Moreover one channel member of each raceway is free to yield or move away from its companion raceway member against the tension 15 of spring 42 so that jamming or sticking of the carrier is prevented in the event of particles of grit, rubber, or the like finding their way into the ball channels.

The stem portion 10 of the carrier 11 is 20 provided at its lower end with a forwardly extending foot 45 having an upstanding flange 46 at its forward end. A transversely extending metal bar 47 is connected midway its ends with the flange 46 by a screw 48.

25 A swinging shift frame of substantially U-shape in plan view is mounted in the main frame forward of the segment carrier. This shift frame comprises a transversely extending rock shaft 49, journalled at its ends on the 30 points of two pivot screws 50 which extend through the side walls 1 of the main frame, and a pair of rearwardly extending sheet metal rock arms 51 fixed on said shaft to rock therewith in unison. The rock arms 51 have 35 reduced end portions 52 fitting loosely in apertures 53 in bar 47 adjacent the opposite ends of the bar. The connection between arms 51 and bar 47 is sufficiently loose to permit the necessary relative movement 40 therebetween due to the swinging movement of the arms and the direct vertical movement of the bar. A coiled spring 54, connected at its upper end with a tension adjusting screw 55 threaded through an arm 45 56 on bracket 22, is secured at its lower end to one of the arms 51 of the shift frame. Spring 54 has sufficient tension to rock the shift frame upwardly and shift the segment carrier and segment to its normal or uppermost position, shown in Figs. 3, 6 and 9, 50 and hold the segment and carrier in this position until the shift frame is rocked downwardly by one of the shift key levers.

The normal or lower case character printing 55 position of the segment is determined by an adjustable stop screw 57 threaded through a yoke 58 formed on bracket 4 and which is adapted to engage an abutment 59 on the type-bar segment 12. A suitable lock nut is 60 preferably screwed on stop 57, as shown, for locking the stop in adjusted position. The lowermost or "Fig." shift position of the segment is determined by an adjustable stop screw 60 threaded through a yoke 61 formed 65 on bracket 4 and adapted to be engaged by

the foot 45 on the carrier, as shown in Fig. 5, to limit the downward movement of the carrier and segment. A suitable lock nut is preferably screwed on stop 60, as shown.

The intermediate or "Cap." shift position 70 of the segment is determined by an adjustable stop screw 62 threaded through the transverse member of a U-shaped sheet metal bail 63 and adapted to be engaged by foot 45, as shown in Fig. 4, to arrest the segment in 75 "Cap." shift position. A suitable lock nut is screwed on stop 62, as shown. The side arms of the bail are connected at their upper ends by two pivot screws 64 with an arm 65 on bracket 22 and with a bracket 66 secured to the right hand side wall of the machine. A pair of coiled springs 67 secured at their forward ends to the side arms of bail 63 and at their rear ends to the rear wall 2 of the main frame normally pull the bail 80 rearwardly to the position shown in Figs. 1, 3 and 4 so that stop 62 is normally in position to arrest the segment and carrier in "Cap." shift position. The rearward movement of the bail under the influence of springs 67 85 is arrested when the bail reaches the position shown in Fig. 3, in which position, the transverse member of the bail is parallel with and a slight distance above lugs 68, projecting forwardly from yoke 61 on bracket 4, the 90 side arms of the bail are vertical, and the rear edge of the forwardly offset transverse member of the bail touches a vertical plane through the pivots 64. This arrangement permits the rearward movement of the bail 100 to normal position without danger of binding and provides a rigid support for the bail and stop 62 thereon when the shift mechanism is operated to position the segment for printing capital letters, as more fully hereinafter 105 described.

Duplicate pairs of shift key levers are provided at opposite sides of the keyboard for rocking the shift frame. The two sheet metal "Cap." shift key levers 69 and the two sheet metal "Fig." shift key levers 70 are pivotally supported at their rear ends on a sheet metal key lever fulcrum bar 71 which extends transversely of the machine and is secured at its ends to the side walls 1 of the main frame. The key levers are pivotally connected with the bar 71 by passing the hook portions 72 on the rear ends thereof through apertures 73 in the fulcrum bar. The levers are guided in slots 74 in brackets 75 secured to the side walls 1 of the main frame and are yieldably held in normal position by individual return springs 76 connected with the levers and brackets 75. Each shift key lever is provided with a lug or abutment 77, the lugs on the levers overlying laterally extending lugs or abutments 78 on the rock arms 51 of the shift frame so that whenever a shift key is depressed the shift frame will be rocked downwardly 120

to pull the carrier and segment downwardly through the medium of bar 47.

When either of the "Cap." shift keys is depressed its supporting lever will rock the shift frame downwardly until foot 45 on the segment carrier strikes the intermediate stop 62 carried by bail 63, the bail remaining stationary as there is no connection between either of the key levers 69 and 10 the bail. When foot 45 strikes stop 62 the long transverse member of the bail will flex slightly until it rests firmly on lugs 68 where it will be held as long as the shift key is held depressed. Lugs 68 thus back up or 15 support the bail and hold stop 62 firmly in proper position. When either of the "Fig." shift keys is depressed the key lever 70 on which it is mounted not only rocks the shift frame downwardly to lower the segment carrier, but also swings the bail 63 forwardly 20 to carry the movable intermediate stop 62 out of the path of foot 45 so that the carrier may be pulled down until foot 45 strikes stop 60. The bail 63 is adapted to be rocked 25 forwardly and upwardly by either "Fig." shift lever to render stop 62 inactive, each of said levers 70 being provided with a bail-operating trip arm 79 extending upwardly and rearwardly from a point adjacent the 30 fulcrum of the lever and having an abutment or vertically extending end portion 80 in contact with the rear face of a lug 81 on the adjacent side arm of bail 63. It will be observed that the bail-restoring springs 67, 35 heretofore referred to, cannot pull the bail rearwardly beyond the position shown in Fig. 3 owing to the engagement of lugs 81 with the end portions 80 of the trip arms 79 formed on key levers 70 and the engagement 40 of the upper edges of said key levers at points forward of their fulcrums with the closed upper ends of slots 74 in the guide brackets 75.

A guide screw 82, the shank of which extends loosely through a curved slot 83 in the pivoted arm 29, is screwed into the rear wall 2 of the main frame. The head of the screw and the rear wall of the frame prevent fore and aft tilting movement of 50 the arm 29 and lateral twisting of the arm which might otherwise take place and cause derangement of the antifriction bearings of the segment carrier. A stop lug 84 is stamped out of the rear wall 2 of the frame 55 adjacent the outer edge of the upper end of arm 29, and a stop lug 85 formed on plate 4 is normally located a little to the right of the forwardly extending portion of the angular arm 35 on the depending portion 10 60 of the segment carrier. These two stop lugs serve to prevent sufficient movement of the arm 29 and segment carrier 11 toward the right to permit the balls to drop from the raceways but permit a slight swinging movement of arm 29 and slight lateral movement

of the carrier 11 to compensate for inaccuracies in the formation of the sheet metal parts and to prevent sticking of the segment carrier should particles of solid matter get into the raceways. 70

What I claim is:

1. In a typewriting machine, the combination of a frame, a support shiftable to vary the relation between type-carrying means and a platen and provided with a pair of ball channels at one side of the center thereof and a single ball channel at the other side of the center thereof, the channels at opposite sides of the center of the support facing outwardly toward the adjacent side of the frame, means on the frame provided with inwardly facing ball channels cooperating with the ball channels on the support to form three raceways, and balls in the raceways. 80

2. In a typewriting machine, the combination of a frame, a vertically shiftable type-segment support having two ball channels facing toward one side of the machine and a third ball channel facing toward the opposite side of the machine, stationary means on the frame having ball channels facing inwardly and cooperating with said first two channels on the support to form ball races, a shiftable raceway member having an inwardly facing ball channel cooperating with said third ball channel on the support to form a ball race, anti-friction balls in the races, and a spring urging said movable raceway member inwardly transversely of the machine. 90

3. In a typewriting machine, the combination of a frame, a support shiftable to change case having ball channels at opposite sides thereof facing outwardly and a depending central portion having a ball channel facing outwardly, raceway members on the frame having inwardly facing ball channels cooperating with one of the side channels on the support and the channel on the depending portion of the support to form two races, a yieldable raceway member on the frame having an inwardly facing ball channel cooperating with the other side channel on the support to form a third ball race, and balls in said races. 110

4. In a typewriting machine, the combination of a frame, a support shiftable to change case having ball channels at opposite sides thereof facing outwardly and a depending central portion having a ball channel facing outwardly, raceway members on the frame having inwardly facing ball channels cooperating with one of the side channels on the support and the channel on the depending portion of the support to form two races, a yieldable raceway member on the frame having an inwardly facing ball channel cooperating with the other side channel on the support to form a third ball 120 125 130

race, balls in said races, and key-operated means connected with the depending portion of said support for shifting the support vertically.

- 5 5. In a typewriting machine, the combination of a support shiftable vertically to change case having laterally extending portions provided with outwardly facing ball channels and a depending portion provided 10 with a ball channel facing toward one side of the machine, stationary means provided with inwardly facing ball channels cooperating with the ball channel on the depending portion of the support and the ball channel 15 on one laterally extending portion of the support to form two ball races, a pivoted raceway member having an inwardly facing ball channel cooperating with the ball channel on the other laterally extending portion 20 of the support to form a third ball race, balls in said races, and a spring normally urging the pivoted raceway member inwardly.
6. In a typewriting machine, the combination of a support shiftable vertically to 25 change case having laterally extending portions provided with outwardly facing ball channels and a depending portion provided with a ball channel facing toward one side 30 of the machine, stationary means provided with inwardly facing ball channels cooperating with the ball channel on the depending portion of the support and the ball channel on one laterally extending portion of 35 the support to form two ball races, a pivoted raceway member having an inwardly facing ball channel cooperating with the ball channel on the other laterally extending portion of the support to form a third ball race, balls in said races, and a spring connected 40 with the pivoted raceway member and the depending portion of the support to urge the same transversely of the machine toward the ball channels on said stationary means.

7. In a typewriting machine, the combination of a support shiftable vertically to change case and having three ball channels two of which face toward one side of the machine and the other of which faces toward the opposite side of the machine, means provided with ball channels cooperating with said first two channels on the support to form raceways, laterally yieldable means 50 provided with a ball channel cooperating with the other ball channel on the support to form a third raceway, balls in the raceways, and key-operated means for shifting the support vertically.

8. In a typewriting machine, the combination of a support shiftable in an up-and-down direction, a type-bar hanger on said support, a three-point antifriction supporting and guiding means for the hanger sup-

port embodying two horizontally aligned ball bearings at opposite sides of the center of the hanger support and a third ball bearing staggered relatively to the other two bearings, and means for automatically taking up wear in all three of said bearings.

9. In a typewriting machine, the combination of a main frame, a support shiftable in an up-and-down direction to vary the relation between type-carrying means and a platen, a pair of side bearings for the support located adjacent opposite sides of the frame, a third side bearing for the support located adjacent the longitudinal center of the frame, each of said bearings comprising a pair of raceway members on the support and frame and a ball in the raceway formed by said members, and means for yieldably urging the support sidewise through the medium of one of the raceway members on the frame.

10. In a typewriting machine, the combination of a main frame, a support shiftable in an up-and-down direction to vary the relation between type-carrying means and a platen, a pair of side bearings for the support located adjacent opposite sides of the frame, a third side bearing for the support located adjacent the longitudinal center of the frame, each of said bearings comprising a pair of raceway members on the support and frame and a ball in the raceway formed by said members, and means for yieldably forcing one of each pair of raceway members toward its companion raceway member.

11. In a typewriting machine, the combination of a main frame, a support shiftable in an up-and-down direction to vary the relation between type-carrying means and a platen, a pair of side bearings for the support located adjacent opposite sides of the frame, a third side bearing for the support located adjacent the longitudinal center of the frame, each of said bearings comprising a pair of raceway members on the support and frame and a ball in the raceway formed by said members, one of said raceway members on the frame being bodily shiftable, and a spring connected with said shiftable raceway member and with the support tending to force said member and support bodily sidewise in the same direction.

12. In a typewriting machine, the combination of a main frame, a sheet metal case-shift support having portions thereof bent at an angle to the body of the support and each formed with a ball channel, sheet metal guide members in the main frame and each having a channel cooperating with one of said channels on the support to form raceways, balls in said raceways, means for yieldably pressing one of said guide members transversely of the frame toward the

adjacent channeled portion of the support, and means for shifting the support to change case.

13. In a typewriting machine, the combination of an upright sheet metal type-bar segment support having portions bent at an angle to the body portion thereof and provided with ball channels facing the sides of the machine, sheet metal guide members 10 having bent portions extending fore and aft of the machine and provided with ball channels cooperating with the ball channels on the bent portions of the support to form races, balls in the races, means for pivotally supporting one of said guide members, and a spring for swinging said pivoted member inwardly transversely of the machine.

14. In a typewriting machine, the combination of a main frame, a type-bar hanger 20 support shiftable in a vertical plane in the main frame, means for guiding the support, a type-bar hanger on the support, a shift frame mounted in the main frame to rock up and down about a horizontal axis extending transversely of the main frame and connected with the hanger support, spring means for normally rocking the shift frame upwardly, a pair of vertically spaced fixed stops for limiting the vertical movement of 30 the hanger support, a bail pivotally supported in the main frame to swing fore and aft of the machine, a stop on said bail for arresting the hanger support at an intermediate position, and a pair of key levers 35 each adapted to engage and rock the shift frame downwardly, one of said key levers being also adapted to rock said bail.

15. In a typewriting machine, the combination of a main frame, a type-bar hanger 40 support shiftable in a vertical plane in the main frame, means for guiding the support, a type-bar hanger on the support, a shift frame mounted in the main frame to rock up and down about a horizontal axis extending transversely of the main frame and connected with the hanger support, spring means for normally rocking the shift frame upwardly, a pair of vertically spaced fixed stops for limiting the vertical movement of 50 the hanger support, a bail pivotally supported in the main frame to swing fore and aft of the machine, a stop on said bail for arresting the hanger support at an intermediate position, spring means for normally 55 swinging said bail in one direction to place the stop thereon in support-arresting position, and a pair of key levers each adapted to engage and rock the shift frame downwardly, one of said levers being unconnected 60 with the bail and the other having an arm for rocking the bail to carry the stop thereon out of support-arresting position.

16. A sheet metal type-bar hanger support provided adjacent its ends with a pair 65 of oppositely facing ball races and having a

depending portion substantially midway its ends provided with a ball race facing in the same direction as one of the end races.

17. A sheet metal type-bar hanger support of approximately Y-shape having an outwardly facing ball race at one side of the central depending portion thereof and a pair of outwardly facing ball races at the ends of the upwardly and outwardly extending portions thereof. 75

18. In a typewriting machine, the combination of an upright sheet metal segment carrier, a type-bar segment on the carrier, said carrier being provided with vertical ball channels adjacent opposite ends of the segment facing the sides of the machine and also having a central portion depending below the segment provided with a vertical ball channel facing one side of the machine, stationary sheet metal guide members provided with vertical ball channels cooperating with the ball channel on the depending portion of the carrier and the similarly facing end channel on the carrier to form races, a yieldably held sheet metal guide member provided with an inwardly facing ball channel cooperating with the other end channel on the carrier to form a race, balls in the races, and key-operated means for shifting the carrier. 80

19. A type-bar segment support comprising a sheet metal plate having portions thereof bent at right angles to the plane of the plate and doubled back upon themselves, the outer part of each doubled portion of the plate having a portion thereof pressed inwardly against the inner part and shaped to form a ball channel. 90

20. In a typewriting machine, the combination of a main frame, a vertically reciprocable type-hanger support, a type-bar hanger on the support, vertically extending raceway members on the support adjacent the ends of the hanger formed with ball channels, raceway members on the frame provided with ball channels, balls in the raceways formed by said raceway members, said support having a central depending portion, a bar extending transversely of the machine held to said depending portion of the support and provided with apertures adjacent its ends, a rock shaft extending transversely of the frame, a pair of rock arms fixed on said shaft at one end and engaging loosely in the apertures in the bar at their other ends, one of said arms having a laterally extending projection thereon, and a key lever adapted to engage said projection to reciprocate the support. 105

21. In a typewriting machine, the combination of a main frame, a vertically reciprocable type-hanger support, a type-bar hanger on the support, vertically extending raceway members on the support adjacent the ends of the hanger formed with ball 110

channels, raceway members on the frame provided with ball channels, balls in the raceways formed by said raceway members, said support having a central depending portion, a bar extending transversely of the machine held to said depending portion of the support and provided with apertures adjacent its ends, a rock shaft extending transversely of the frame, a pair of rock arms fixed on said shaft at one end and engaging loosely in the apertures in the bar at their other ends, each of said arms having an outwardly projecting abutment thereon, and a pair of key levers fulcrumed in the main frame at their rear ends at opposite

sides of the main frame and overhanging the abutments on the rock arms.

22. A sheet metal type-bar segment carrier comprising a flat plate having portions thereof bent at right angles to the plane of the plate and doubled back upon themselves, the doubled back part of each of said portions being slit adjacent both ends to form ball stop lugs and being pressed against its companion part along a line extending between said lugs to form a ball channel. 20 25

In testimony whereof I hereunto affix my signature.

FRANK H. ARMSTRONG.
